MEANS FOR PREVENTING VAPOR LOCK IN
INTERNAL COMBUSTION ENGINES

Adolph V. Mitterer, Denver, Colo.

Application June 1, 1936, Serial No. 82,947

18 Claims. (Cl. 158—36.4)

This invention relates to improvements in fuel feed systems for internal combustion engines and relates more particularly to the addition of means for preventing the formation of a condition known as a "vapor lock".

The fuel employed for the production of power in internal combustion engines is limited, almost entirely to gasoline which is a mixture of liquids each of which has its own definite boiling point. 10 The lighter portions of this mixture may boil at 120 degrees F. or less, while the heavier portions may not boil until a temperature of 400 degrees F. is reached.

In an ordinary automobile, on hot days, radiation from the road and the resulting hot air close to the road, assisted by air warmed by passing through the radiator and over the engine may raise the fuel in the gasoline tank as much as 25 degrees F. and therefore if the air 15 temperature is 100 degrees F., the fuel may be 125 degrees F., or above the boiling point of the most volatile constituents.

The fuel line from the tank to the carburetor as well as the pump and the carburetor are 20 heated by the air and also by conduction from the engine as well as by radiation from the hot engine parts. As a result of the high temperature of the parts through which the fuel has to flow, a large amount of vapor is formed which 25 interferes with the operation of the pump which is designed to handle liquid and not vapor.

In any fuel feed system for supplying volatile liquid fuel to an internal combustion engine, there is a constant danger that a portion of the 30 liquid fuel will vaporize during its passage from the supply tank to the carburetor.

When enough vapor forms in the delivery system, the normal flow of the liquid fuel may be 35 seriously retarded and even completely stopped. 40 This is most likely to occur in warm weather and in portions of the delivery system located near the engine or the exhaust manifold and pipe, and when it occurs, produces what is called a "vapor lock".

In systems using some form of pump for fuel 45 delivery, the formation of vapor in the fuel lines may cause the pump to cease entirely delivering fuel or may cause it to deliver it irregularly.

It is one object of this invention to produce 50 a fuel feed system having means for separating the vapors from the liquid fuel, condensing and returning them to the fuel line, so as to prevent the formation of a "vapor lock".

Where gasoline is supplied to a carburetor by

means of a pulsating pump, either of the plunger or diaphragm type, it is supplied intermittently and in a pulsating manner.

It is another object of this invention to produce a fuel feed system provided between the 5 pump and the carburetor with an air or vapor cushion, similar to those employed in connection with water pumps, for the purpose of smoothing the pump impulses.

The above and any other objects that may 10 become apparent as the description proceeds are attained by means of a construction and an arrangement of parts that will now be described, reference for this purpose being had to the accompanying drawings in which the invention has 15 been illustrated, in its preferred form, and in which

Figure 1 is a diagrammatic view showing a 20 fuel feed system in accordance with this invention;

Figure 2 is a view, to a larger scale, showing the heat radiator or condenser in section and showing one way of attaching it to the feed pipe;

Figure 3 is a section taken on line 3—3, Figure 2;

Figure 4 is a side elevation of a connector like that employed in Figure 2, but with the condenser removed and the side opening plugged;

Figure 5 shows a fuel feed system of the vacuum tank type, formed in accordance with this 30 invention;

Figure 6 is a section, similar to that shown in Figure 2, to a smaller scale, and shows a modified form of condenser;

Figure 7 is a section taken on line 7—7, Figure 35 6;

Figure 8 is a section similar to that of Figure 6 and shows another form of condenser;

Figure 9 shows a slight modification of the construction shown in Figure 1; and

Figure 10 is a vertical section of a condenser 40 involving a slight modification of that shown in Figure 2.

In the drawings numeral 5 designates an internal combustion motor having a carburetor 6 and a fuel pump 7. The fuel tank 8 is located at a lower level than the carburetor and fuel is conducted from the tank to the carburetor by the fuel pipe 9. A pipe 10 connects the pump with the carburetor. At some suitable point in 50 the fuel line, a condenser 11 is connected in the manner shown in Figures 2, 6 and 8.

The fuel line is cut and the ends are connected by means of a T 12, or 12a in Figure 2. The pipe 10 has also been shown as formed in two parts 45

connected by a T 12 and provided with a condenser 11.

When the engine operates the pump 7 is also operating for the purpose of transferring liquid fuel from the tank 8 to the carburetor. On the intake side of the pump the pressure in the line 9 is less than atmospheric, so that the air pressure on the fuel in tank 8 will produce a flow to the pump. If the gasoline is very hot, as it often becomes in summer, it vaporizes freely and the rate of vaporization is greater in the feed line 9 than in the tank, due to the decreased pressure therein. It is evident that if line 9 fills with vapor the pump will be pumping vapor instead of gasoline, and since it is designed for pumping the liquid fuel, its capacity is too small to supply the engine with sufficient fuel to run, with the result that it will stop. This condition is called a "vapor lock".

When the fuel line is provided with a condenser like either of those shown in Figures 2, 6 or 8, the vapor will enter the condenser and be cooled whereupon it will be condensed and flow to the pump as a liquid, thereby enabling the pump to supply the necessary amount of fuel to the motor.

The condenser 11, connected with the delivery pipe 10, serves to smooth the pulsations due to the operation of the pump.

Since any pump operates by reducing the pressure in the feed line, it is possible to substitute for the mechanical pump shown in Figure 1, a vacuum tank 13, like that shown in Figure 5. The diagrammatic view shown in Figure 5 differs from that shown in Figure 1 in this, that instead of a mechanical pump a vacuum tank is employed, which is the mechanical equivalent of a pump for the purpose of raising the gasoline or other liquid fuel.

The vacuum tank 13 is connected with the intake manifold 14 by a tube 15 and a tube 10 connects the vacuum tank with the carburetor. In Figure 5, no condenser has been shown in the fuel line, but can be applied to it in the manner shown in Figure 1.

In climates where the temperature does not become excessive it is sometimes sufficient to provide the fuel line with a section 12a (Figure 4), provided with radiating fins which serve to dissipate any excessive amount of heat in the fuel and to condense any vapors that may form.

It will be seen from Figures 2, 6 and 8 that the condensers 11 are all provided with radiating fins or flanges 17.

The condenser shown in Figure 8 is formed from a tubular cylindrical body member 18 and a cap 19 connected thereto by a press fit joint. The condenser shown in Figure 6 has a tubular member 18 that is the same as that shown in Figure 8 but the cover or cap 19a differs from that employed in Figure 8 in this, that instead of being concave on its inner surface, it is provided with an inwardly projecting plug 20 that terminates in a conical end portion.

The condenser illustrated in Figure 2 comprises a hollow cylindrical member 18a having a section 21 at its upper end threaded. The diameter of the threaded section is somewhat greater than that of the opening beneath so as to provide a shoulder 22.

The top 19b is provided with a threaded extension 23 that cooperates with the threaded section 21, and its inner surface is spherically concave.

A conical partition 24 has its base provided

with a flange 25 that is clamped between the shoulder 22 and the end of the threaded extension 23. The partition has a number of small openings 26 and is provided at its apex with a large opening 27. The lower end of the cylindrical wall of member 18a terminates in a shoulder on which the screen 28 rests.

Instead of mounting the condenser 11 in the manner shown in Figure 1, it can be mounted on top of the pump 7 in the manner shown in Figure 9.

In Figure 10, a modified form of the construction illustrated in Figure 2 has been shown, in which the partition 24 has been reversed and instead of employing the screen 28, a pipe 28a extends upwardly from the opening in the bottom of the condenser, and terminates underneath the opening 27 in the partition 24. Pipe 28a is provided with a plurality of openings 30 through which the condensed fuel can return to the fuel line.

During operation, the fuel 29 stands approximately at the levels indicated in Figures 2, 6 and 8.

Any vapors in line 9 pass into the condenser through the opening in the bottom, and condense 25 when they enter the cool interior of the heat radiator.

Any vapor that passes into the dome, above the partition 24 condenses and returns to the liquid through the opening 27.

The screen 28 prevents any solid matter from getting into the feed line during installation or when the top is removed, and functions to facilitate the cooling and condensing of the vapor by separating it and conducting heat units therefrom. The partition 24 divides the condensing chamber into a lower primary chamber and an upper secondary chamber and functions to retard the upward flow of vapor in the condenser and helps to cool and condense the vapor by separating it and conducting heat units therefrom to the exterior walls for radiation into the atmosphere.

Having described the invention, what is claimed as new is:

1. A heat radiator comprising an elongated substantially cylindrical body member having one end closed and the other open, the closed end having a hole for the reception of a pipe connection, the open end having a threaded section of larger diameter, whereby a shoulder is formed, a perforated conical partition member having a circular flange resting on the shoulder, and a cap for closing the open end, the cap having a threaded section for engaging with the threaded section in the body member and for holding the partition in place, the body member and the cover having heat radiating fins.

2. A heat radiator and condenser comprising a chambered body member for use in a vertical position, the top being closed and the bottom provided with an opening, a perforated partition extending transversely of the chamber, dividing it into an upper and a lower compartment, and a pipe having its lower end positioned in the opening in the bottom, and its upper end terminating adjacent the partition, the pipe wall having a plurality of openings adjacent the bottom of the condenser.

3. A heat radiator and condenser comprising a chambered body member for use in a vertical position, the top being closed and the bottom provided with an opening, a conical perforated partition extending transversely of the chamber, at a point near the upper end thereof, the ver-

tex of the partition being at the top and perforated, and a pipe having its lower end in the opening in the bottom and its upper end terminating adjacent the partition, the wall of the 5 pipe being provided with openings directly above the bottom of the condenser.

4. A heat radiator and condenser comprising a chambered body member for use in a vertical position, the top being closed and the bottom 10 provided with an opening, and a pipe having its lower end positioned in the opening in the bottom and its upper end terminating in the upper portion of the chamber, the pipe wall having a plurality of openings adjacent the bottom of the 15 condenser.

5. In a liquid fuel supply system for internal combustion engines, in which there is a forced movement of a volatile fuel through a conduit from a supply tank to a carburetor, a chamber 20 provided with heat-conductive walls positioned above the fuel stream in communicating relation to the conduit to receive volatiles rising therefrom, and heat-dissipating means on the exterior of the chamber to induce condensation 25 of volatiles within the chamber.

6. In a liquid fuel supply system for internal combustion engines, in which there is a forced movement of a volatile fuel through a sealed conduit from a supply tank to a carburetor, a chamber 30 provided with heat-conductive walls positioned above the fuel stream in communicating relation to the conduit to receive volatiles rising therefrom, and heat-dissipating means on the exterior of the chamber to induce condensation 35 of volatiles within the chamber.

7. In a liquid fuel supply system for internal combustion engines, in which there is a forced movement of a volatile fuel through a conduit from a supply tank to a carburetor, a condensation 40 chamber provided with heat-conductive walls positioned above the conduit, a conductive connection between the chamber and the conduit to admit volatiles rising from the fuel stream into said chamber, and means cooperative with 45 the chamber walls to dissipate heat from the trapped volatiles, whereby to induce condensation thereof and subsequent return to the fuel stream.

8. In a liquid fuel supply system for internal 50 combustion engines, in which there is a forced movement of a volatile fuel through a conduit from a supply tank to a carburetor, a chamber provided with heat-conductive walls positioned above the fuel stream in communicating relation 55 to the conduit to receive volatiles rising therefrom, a partition dividing the chamber into condensation and supply compartments, and heat-dissipating means on the exterior of the chamber to induce condensation of volatiles 60 within the chamber.

9. In a liquid fuel supply system for internal combustion engines, in which volatile fuel is moved through a conduit from a supply tank to a 65 pump, a chamber provided with heat-conductive walls positioned beyond the conduit between the tank and the pump in communicating relation to the conduit to receive volatiles rising therefrom, said volatiles being maintained in said chamber at substantially atmospheric pressure, and heat-dissipating means on the exterior of the chamber to induce condensation of volatiles therein.

10. In a liquid fuel supply system for internal combustion engines, in which volatile fuel is moved through a conduit from a supply tank to a 70 pump, a chamber provided with heat-conduc-

tive walls positioned beyond the conduit between the tank and the pump, a conductive connection between the chamber and the conduit to admit volatiles rising from the fuel stream into the chamber, said volatiles being maintained at substantially atmospheric pressure in said chamber, and heat-dissipating means on the exterior of the chamber to induce condensation of volatiles 5 therein.

11. A device for preventing vapor lock in the 10 fuel line of an internal combustion engine, comprising a hollow body of heat-conductive material adapted for connection with a fuel line at a side thereof to entrap and condense volatiles admitted therefrom, the body having an irregular exterior 15 surface providing a relatively large superficial area facilitating transfer of heat units from the body.

12. A device for preventing vapor lock in the 20 fuel line of an internal combustion engine, comprising a hollow body of heat-conductive material adapted for connection with a fuel line at a side thereof to entrap and condense volatiles admitted therefrom, the body having heat-dissipating 25 means on its exterior surface to facilitate transfer of heat units from the body, and a conical partition in the body dividing the same into condensation and supply compartments.

13. A device for preventing vapor lock in the 30 fuel line of an internal combustion engine, comprising a hollow body of heat-conductive material adapted for connection with a fuel line at a side thereof to entrap and condense volatiles admitted therefrom, the body having heat-dissipating 35 means on its exterior surface to facilitate transfer of heat units from the body, and a conical partition in the body dividing the same into condensation and supply compartments, there being a plurality of apertures in the partition for passage of matter therethrough in opposite directions.

14. A device for preventing vapor lock in the 40 fuel line of an internal combustion engine, comprising a hollow body of heat-conductive material adapted for connection with a fuel line at a side thereof to entrap and condense volatiles admitted therefrom, the body having heat-dissipating 45 means on its exterior surface to facilitate transfer of heat units from the body, and an apertured partition in the body dividing the same into condensation and supply compartments.

15. In a liquid fuel supply system for internal 50 combustion engines, in which volatile fuel is moved through a conduit from a pump to a carburetor, a chamber provided with heat-conductive walls positioned beyond the conduit between the pump and the carburetor in communicating relation to the conduit to receive volatiles rising therefrom, said volatiles being maintained in said chamber at substantially atmospheric pressure, 55 and heat-dissipating means on the exterior of the chamber to induce condensation of volatiles 60 therein.

16. In a liquid fuel supply system for internal 65 combustion engines, in which volatile fuel is moved through a conduit from a pump to a carburetor, a chamber provided with heat-conductive walls positioned beyond the conduit between the pump and the carburetor in communicating 70 relation to the conduit to receive volatiles rising therefrom, said volatiles being maintained in said chamber at substantially atmospheric pressure, heat-dissipating means on the exterior of the chamber to induce condensation of volatiles 75 therein, and means in the chamber in commun-

cation with the conduit for returning the condensed product to the conduit under the suction influence of the flow of fuel therethrough.

17. In a liquid fuel system for internal combustion engines, in which volatile fuel is moved through a conduit from a supply tank to a pump, a chamber provided with heat-conductive walls positioned beyond the conduit between the tank and the pump in communicating relation to the conduit to receive volatiles rising therefrom, said volatiles being maintained in said chamber at substantially atmospheric pressure, heat-dissipating means on the exterior of the chamber to induce condensation of volatiles therein, and means in the chamber in communication with the conduit for returning the condensed product to the conduit under the suction influence of the flow of fuel therethrough.

18. In a liquid fuel supply system for internal combustion engines, in which there is a forced movement of volatile fuel through a conductive element, a chamber provided with heat-conductive walls positioned above the element in communicating relation thereto to receive volatiles rising therefrom, said volatiles being maintained in said chamber at substantially atmospheric pressure, heat-dissipating means on the exterior of the chamber to induce condensation of volatiles therein, and means in the chamber in communication with the conductive element for returning the condensed product to the conduit under the suction influence of the flow of fuel therethrough.

ADOLPH V. MITTERER.
